UNITED STATES PATENT OFFICE.

JOHN FLANAGAN, OF NEWBURG, NEW YORK.

STOP-COCK.

SPECIFICATION forming part of Letters Patent No. 242,910, dated June 14, 1881.

Application filed February 23, 1881. (Model.)

To all whom it may concern:

Be it known that I, JOHN FLANAGAN, of Newburg, in the county of Orange and State of New York, have invented a new and useful Improvement in Stop-Cocks, of which the following is a full, clear, and exact description.

The drawing is a plan view, partly in section, of my improvement.

The object of this invention is to facilitate the thawing out and removing obstructions from water-pipes.

The invention consists in constructing a stop-cock with an inclined or slightly-curved branch pipe, so that a steam-tube can be readily inserted through or a force-pump connected with the stop-cock for thawing out or removing obstructions from pipes, as will be hereinafter fully described.

A represents the body of the stop-cock, the ends of which are constructed in the ordinary manner, so that the said ends can be secured to the adjacent ends of a pipe.

B is the plug, which is constructed and operated in the ordinary manner.

In the body A is formed a branch, C, projecting in the direction of the middle part of the stop-cock and inclined or slightly curved outward at each angle, as shown in the drawing, so that a steam-tube can be readily inserted through the stop-cock to thaw out the pipe when frozen.

This improvement is especially intended for service-pipes, so that, should the said pipes freeze between the house and the water-main, the said pipes can be thawed out without its being necessary to dig up the street or cut the pipe, thus avoiding great annoyance and expense.

Another advantage of my improvement is the facility which it gives an operator for removing obstructions from pipes.

With this construction, should a pipe become obstructed, the operator can apply a force-pump to the branch C and force the obstruction back into the main.

The branch C is closed with a screw cap or plug, D, so that it can be readily opened when required.

Having thus described my invention, I claim as new and desire to secure by Letters Patent—

As an improved article of manufacture, a stop-cock having the end-tapered body A, the median plug B, and the internally end-threaded inclined pipe C, provided with screw-plug D, as shown and described.

JOHN FLANAGAN.
